US00D864706S

(12) **United States Design Patent** (10) **Patent No.:** **US D864,706 S**
(45) **Date of Patent:** **** Oct. 29, 2019**

(54) **FENCE STRETCHING DEVICE**

(71) Applicant: **BUSINESS INNOVATIONS, LLC**,
Southwest City, MO (US)

(72) Inventors: **Jim Haworth**, Southwest City, MO
(US); **Kent Farmer**, Jay, OK (US)

(73) Assignee: **BUSINESS INNOVATIONS, LLC**,
Southwest City, MO (US)

(**) Term: **15 Years**

(21) Appl. No.: **29/678,280**

(22) Filed: **Jan. 28, 2019**

Related U.S. Application Data

(63) Continuation-in-part of application No. 29/594,940,
filed on Feb. 23, 2017, now Pat. No. Des. 839,088.

(57) **CLAIM**

The ornamental design for a fence stretching device, as
shown and described.

DESCRIPTION

A portion of the disclosure of this patent document contains
material which is subject to intellectual property rights such
as but not limited to copyright, trademark, and/or trade dress
protection. The owner has no objection to the facsimile
reproduction by anyone of the patent document or the patent
disclosure as it appears in the Patent and Trademark Office
patent files or records but otherwise reserves all rights
whatsoever.

FIG. 1 is a perspective view of a fence stretching device with
the adjustment arm inserted laterally showing my new
design;

FIG. 2 is another perspective view of the fence stretching
device thereof, with the adjustment arm inserted longitudinally;

FIG. 3 is another perspective view of the fence stretching
device thereof, with the adjustment arm inserted laterally;

FIG. 4 is another perspective view of the fence stretching
device thereof, with the adjustment arm inserted longitudinally;

FIG. 5 is a front perspective view of the fence stretching
device with the adjustment arm removed;

FIG. 6 is a rear perspective view thereof;

FIG. 7 is another perspective view thereof;

FIG. 8 is another perspective view thereof;

FIG. 9 is a bottom view thereof, the top view being a mirror
image of the bottom view;

FIG. 10 is a front view thereof;

FIG. 11 is a rear view thereof;

FIG. 12 is a right side view thereof, the left side view being
a mirror image of the right side view;

FIG. 13 is a perspective view of the adjustment arm com-

ponent of the fence stretching device;

(Continued)

FIG. 14 is a bottom view thereof, the top view being a mirror image of the bottom view;
 FIG. 15 is a front view thereof;
 FIG. 16 is a rear view thereof; and,
 FIG. 17 is a right side view thereof, the left side view being a mirror image of the right side view.
